CLAIM

The ornamental design for a shuffle for connecting nodes in a direct interconnect network, as shown and described.

DESCRIPTION

FIG. 1 is an upper, right side perspective view of a shuffle for connecting nodes in a direct interconnect network; FIG. 2 is a lower, left side perspective view thereof; FIG. 3 is a front side view thereof; FIG. 4 is a back side view thereof; FIG. 5 is a left side view thereof; FIG. 6 is a right side view thereof; FIG. 7 is a top plan view thereof; and, FIG. 8 is a bottom plan view thereof.

The broken lines shown in the drawings depict portions of the shuffle for connecting nodes in a direct interconnect network that form no part of the claimed design. The shade lines indicate the character and contour of the surfaces represented, not to be confused with surface ornamentation.
